UNITED STATES PATENT OFFICE

EDWARD KIRBY BOTTLE, OF ELMIRA, NEW YORK, ASSIGNOR TO AMERICAN SALES BOOK COMPANY, LIMITED, OF TORONTO, CANADA, A CORPORATION OF ONTARIO, CANADA

STRIP SUPPORT FOR AUTOGRAPHIC REGISTERS

Application filed April 22, 1925, Serial No. 24,938. Renewed May 29, 1930.

This invention relates to improvements in autographic registers or the like and more particularly in some of its details to such registers portable in nature or capable of being carried in the hand when in use.

It is a general object of the invention to provide a register of the class mentioned which is simple and inexpensive in construction, convenient and efficient in use, and strong, yet so light as to render it readily portable and capable of being carried in the hand while in use without undue strain or fatigue upon the user.

A further object is to provide a light, strong, portable device of the class mentioned especially adapted for use in connection with delivery wagons or in coal or lumber yards or similar places where portability is a desirable factor, or for use as a substitute for the ordinary sales book.

A further object is to provide an improved arrangement for supporting one or more transfer or carbon strips in correct position over the writing table so as to minimize tearing or wrinkling of the transfer strips and to avoid interference with the record strips or with the feeding movement thereof.

It is also an object of the invention to provide an improved arrangement for binding the transfer strip or strips in position at both sides of the writing table so the strips are at all times positively retained in correct operative position.

It is also an object to provide an improved support and housing or compartment for a roll or similar supply of transfer strip or carbon paper so as to protect the same from dirt and moisture or from tearing or other injury.

Other objects will be in part pointed out in connection with the following detailed description and will be in part obvious in connection therewith.

The invention accordingly comprises the features of construction, combinations of elements, and arrangement of parts, which will be exemplified in the construction herein-after set forth and the scope of the application of which will be indicated in the claims.

For a more complete understanding of the

nature and objects of the invention reference is had to the following detailed description and to the accompanying drawings disclosing illustrative but preferred embodiments of the invention, and in which

55

Figure 1 is a side elevation of an autographic register embodying the invention, parts being broken away and in section;

Fig. 2 is a top plan view thereof;

Fig. 3 is an end elevation looking at the right end of Fig. 1, parts being in transverse section;

Fig. 4 is a fragmentary detail section on the line 4—4 of Fig. 2 looking in the direction of the arrows;

Fig. 5 is a section on the line 5—5 of Fig. 4 looking downwardly;

Fig. 6 is a view of a portion of a record strip for use in the register;

Fig. 7 is a sectional view corresponding to Fig. 5 but showing a modification of the housing for the transfer strip supply; and

Fig. 8 is a fragmentary side elevation corresponding to Fig. 1 but showing a modification of the transfer strip clamp.

75

Referring to the drawing for a detailed description of the embodiments there shown, there is represented an autographic register having a casing preferably made of some light, strong material, such as sheet metal, which is readily bent and shaped to form the walls and other parts of the register. Bottom, top, side and end walls are provided, the top wall forming a platen or writing table 10 overlying an interior compartment

80

adapted for the reception of a supply of record strip 11 which may be in the form of a zigzag supply pack 12 indicated in dot and dash outline in Fig. 1. The casing may be made so light and small as to be readily portable or capable of being carried in one hand while the other hand makes an entry upon a record strip carried by the register.

85

A passageway is provided at one end of the casing for access to the interior compartment and for loading the supply pack 12 into position within the register, and a door or closure 13 is provided for such passageway being hinged at its lower edge as at 14 and spring pressed toward closed position by

90

95

100

means of a spring 15. The supply pack in horizontal dimension is practically equal to that of the interior compartment, being retained at the forward end of the compartment by a flange 18' upturned from the bottom plate of the register. The door 13 preferably terminates short of the top wall or writing table 10 leaving a slot or opening 16 for passage of the transfer strips 11 from the interior compartment to the overlying writing table.

At a point near to the slot 16 at the forward end of the register, the writing table 10 is provided with a downturned flange 17 preferably inwardly inclined and forming a transverse edge or apex over which the strips 11 pass. This edge forms a guide over which the strips turn in their passage from the compartment to the writing table. The upper edge of the door forms a guide for the strips prior to reaching the transverse apex formed by the flange 17 and a second guide for the strips is positioned beyond said apex, being formed by a transverse plate 18 secured to the register and spaced slightly above the writing table 10.

At the rear end of the writing table is a pivoted clamping plate 19 overlying the strips 11 and adapted to contact therewith to hold them in correct position on the writing table, said plate having angularly disposed depending supporting arms pivoted to the sides of the register, one of said arms having an outwardly extending flange forming a lug 20 for manual operating of the clamping plate. The clamping plate is preferably spring pressed downwardly into clamping position, and when the strips are fed forwardly, the forward edge of the clamping plate functions as a tearing edge across which the projecting strip ends may be severed.

The writing table 10 is provided with a notch 21 underlying the clamping plate 19 whereby the ends of the record strips 11 may be grasped to feed them forward manually after severance of the projecting strip ends. The end wall is similarly notched under the notch 21 as at 21'.

There may be several superposed record strips 11 each being preferably provided with blank forms and having apertures 22 for filing the severed sheets as upon filing pins or the like.

Transfer strips, such for example as carbon paper strips 23, may be disposed between adjacent record strips over the writing table so as to transfer to the lower record strips the record made upon the uppermost record strip by writing thereon. For housing and protecting a supply roll 24 of transfer strips a housing and support 25 is provided, being disposed at one side of the writing table and extending longitudinally of the register. A simple and effective construction for this housing is disclosed, including a plate 26

which may as shown be integral with the side plate 27 of the register, being bent into tubular or cylindrical form to provide a compartment for the roll of transfer strip. The plate 26 is discontinuous at the upper side of the tubular housing providing an opening for the reception of the roll and through which the strips extend to writing position over the writing table. The end walls 28 of the housing 25 are preferably integral at one edge thereof with the side wall 26 abutting or overlapping, at other edges thereof, the ends of the side wall of the housing, as shown in Fig. 5. A cover 29 is provided for the housing opening conforming substantially to the housing contour, being substantially cylindrical and mounted upon the housing for rotation on its longitudinal axis and sliding over the wall 26 of the housing to close and open said housing, as best seen in Figs. 3 and 4. The cover 29 is substantially co-extensive longitudinally with the side walls, being provided at its ends with inturned annular flanges which frictionally engage the end walls 28 of the housing. In order to further assure the retention of the closure 29 in closed position, a friction catch 31 is provided which may be struck up from the surface of the housing wall, lying in position to engage the lower edge of the closure 29, (see Fig. 3), thus holding the closure in closed position. It will therefore be seen that the closure 29 is retained with its upper edge in engagement with the transfer strips 23 extending from the housing so as to tightly clamp them in position over the writing table.

In Fig. 7 is shown a modification of the housing construction for the transfer strip supply in which the cover 29a is provided with end walls 32 overlapping the end walls 28a of the tubular housing and being pivoted thereto by pivot pins 33. The end walls 28a and 32 are held in close frictional engagement thereby tending to hold the cover in close position.

A clamp is provided on the side of the register opposite to the transfer strip housing 25 for holding the free ends of the carbon strips 23, being illustrated in Figs. 1, 2 and 3 as a clamping plate 34 pivoted at 35 to the register and spring pressed into clamping position by springs 36. The upper edge of the clamping plate is slightly inwardly inclined and offset so as to grip the strips 23 against the side of the register. A flange 37 is bent outwardly from the body of the plate 34 under which the free ends of the transfer strips 23 may extend. The outer edge of this flange may be employed as a tearing edge for severing the excess free ends of the transfer strips, and furthermore said flange may be employed as an operating handle for drawing the clamping plate 34 away from clamping position. The flange 37 also serves as a reinforcing and rigidifying rib for the clamping

plate, stiffening the latter and preventing warping thereof.

It will thus be seen that the carbon strips are securely clamped along the width thereof at both sides of the writing table preventing wrinkling or tearing of the strips and avoiding displacement thereof which might interfere with the feeding of the record strips or with an entry of a record thereon. Also, the transfer strip supply 24 is completely enclosed in a tight enclosure which effectively excludes dirt and moisture and protects the strip from injury.

A modified form of clamp for the free ends 15 of the transfer strips opposite to the housing 25 is shown in Fig. 8, and includes a clamping bar 38 pivoted at 39 to the side of the register and having a keeper 40 for receiving and holding the free end. The ends 20 of the transfer strips are placed under the clamping bar 38 which is then moved to closed position in its keeper 40, as shown, thus clamping the ends of the strip tightly against the side of the register.

25 Since certain changes may be made in the above construction and different embodiments of the invention could be made without departing from the scope thereof, it is intended that all matter contained in the 30 above description or shown in the accompanying drawing shall be interpreted as illustrative and not in a limiting sense.

It is also to be understood that the following claims are intended to cover all of the 35 generic and specific features of the invention herein described, and all statements of the scope of the invention which, as a matter of language, might be said to fall therebetween.

Having described my invention, what I 40 claim as new and desire to secure by Letters Patent is:

1. In an autographic register, in combination, a writing table over which a record strip may be fed, a housing supported by said register and forming a transfer strip supply compartment at one side of said table having an opening through which the supply may be inserted and a cover for said compartment opening adapted to clamp the transfer strip 45 adjacent to said table to hold said strip in operative position and having frictional engagement with said housing to retain it in clamping position.

2. In an autographic register, in combination, a writing table over which a record strip may be fed, a cylindrical housing supported by said register and forming a transfer strip supply compartment at one side of said table having an opening through the side of the 50 housing, a cover for said compartment opening mounted for axial rotation upon said cylindrical housing to open or close said opening and when in closed position being adapted to clamp the transfer strip adjacent to said table to hold said strip in operative position,

and means for holding said cover in clamping position.

3. In an autographic register, in combination, a writing table over which a record strip may be fed, a tubular housing for a transfer strip supply having an opening in the side thereof for reception of a roll of transfer strip and a cylindrical cover for said housing having its cylindrical wall concentric with and arranged in overlapped relation with the 70 wall of said housing and being axially movable into position to clamp the transfer strip adjacent said writing table.

4. In an autographic register, in combination, a writing table over which a record strip 80 may be fed, a tubular housing for a transfer strip supply having an opening in the side thereof for reception of a roll of transfer strip, a cylindrical cover for said housing movable into position to clamp the transfer strip adjacent said writing table, and a friction strip mounting for said cover to hold it in strip clamping position.

5. In an autographic register, in combination, a writing table over which a record strip 90 may be fed, a tubular housing for a transfer strip supply having an opening in the side thereof for reception of a roll of transfer strip, a cylindrical cover for said housing rotatable into position to clamp the transfer strip adjacent said writing table, and a catch between said housing and said cylindrical cover for securing the latter in clamping position.

6. In an autographic register, in combination, a tubular housing for a transfer strip supply mounted upon the register and having a cylindrical wall and spaced ends, said wall being discontinuous to provide an opening in the side of the housing for the reception of the transfer strip supply and a cylindrical cover for said opening having a friction mounting on said end walls to frictionally hold said cover in closed position.

7. In an autographic register, in combination, a tubular housing for a transfer strip supply mounted on the register and having a cylindrical wall and spaced ends, said wall being discontinuous to provide an opening in the side of said housing for reception of the transfer strip supply and a cylindrical cover for said opening having its end margins bent over the edges of said end walls and forming a friction mounting for said cover.

8. In an autographic register, in combination, a tubular casing for a transfer strip supply mounted upon the register and having a cylindrical wall and spaced ends, said wall being discontinuous to provide an opening in the side of the housing for the reception of the transfer strip supply, and a cylindrical cover for said opening having a friction catch for holding said cover in closed position.

9. In an autographic register, in combination, a tubular casing for a transfer strip sup-

- ply mounted upon the register and having a cylindrical wall and spaced ends, said wall being discontinuous to provide an opening in the side of the housing for the reception of the transfer strip supply, and a cylindrical cover for said opening having end walls lapping and frictionally engaging said first mentioned end walls and pivotally connected thereto.
10. In an autographic register, in combination, a tubular casing for a transfer strip supply mounted upon the register and having a cylindrical wall and spaced ends, said wall being discontinuous to provide an opening in the side of the housing for the reception of the transfer strip supply, and a cylindrical cover for said opening having its edge positioned to contact with the transfer strip extending from said housing to hold said strip in operative position.
11. In an autographic register, in combination, a tubular housing for a transfer strip supply mounted on the register and having a cylindrical wall discontinuous to provide an opening in the side of the housing for reception of the transfer strip supply, and a cylindrical cover for said opening slidable over said housing wall to open and close said opening.
12. In an autographic register, in combination, a tubular housing for a transfer strip supply mounted on the register and having a cylindrical wall discontinuous to provide an opening in the side of the housing for reception of the transfer strip supply, a cylindrical cover for said opening rotatably mounted upon said housing to cover and uncover said opening, and a friction catch for holding said cover closed.
13. In an autographic register, in combination, a tubular housing for a transfer strip supply including a plate secured at one edge to the register and being bent to provide a compartment with a receiving opening at one side and a cover for said housing slidably mounted thereon to cover and uncover said opening.
14. In an autographic register, in combination, a tubular housing for a transfer strip supply including a plate secured at one edge to the register and being bent to provide a compartment with a receiving opening at one side and a cover for said opening rotatably mounted upon said housing to cover and uncover said opening and having an edge positioned to contact with and grip the transfer strip extending from said housing to hold said strip in operative position.
15. In an autographic register, in combination, a writing table over which a record strip may be fed, a spring pressed clamp arranged in upright position against the side of the register and pivotally mounted, and having an upper contact part to engage a transfer strip in clamping relation, and an outstanding angularly disposed flange on said clamp intermediate said contact part and the pivotal mounting thereof, over which the free ends of the transfer strip may be severed.
16. In an autographic register, in combination, a strip clamp including a plate having a clamping edge offset from the plate body for clamping the strip against the register and a reinforcing flange arranged at an angle to the body of said plate and outstanding thereon so as to form a combined strip tearing edge and operating handle for said clamp.
17. In an autographic register, in combination, a strip clamp having a clamping surface for engaging a strip in clamping relation, said clamp being in the form of a plate having an integral portion thereof, intermediate its edges bent outwardly to form a tearing edge positioned to tear a strip so as to leave a strip end in position to be grasped when the clamp is in clamping position.
18. In an autographic register, in combination, a writing table, a spring pressed clamp positioned against the side of the register and pivotally mounted at its lower edge below said writing table, said clamp having a contact part at one edge thereof to engage and clamp a transfer strip, and an outstanding angularly disposed flange on said clamp intermediate said contact part and the pivotal mounting thereof, said outstanding flange forming a severing member for the transfer strip.
- In testimony whereof I affix my signature.
- EDWARD KIRBY BOTTLE.
